UNITED STATES PATENT OFFICE.

GEORGE W. SLEEPER, OF WESTBOROUGH, MASSACHUSETTS, ASSIGNOR OF
ONE-HALF TO WILLIAM A. REED, OF SAME PLACE.

MACHINE FOR SPLITTING THE UPPERS FOR SHOES.

SPECIFICATION forming part of Letters Patent No. 320,407, dated June 16, 1885.

Application filed October 11, 1884. (No model.)

To all whom it may concern:

Be it known that I, GEORGE W. SLEEPER, of Westborough, in the county of Worcester and State of Massachusetts, have invented a new and useful Improvement in Manufacture of Shoes; and I do hereby declare that the following is a full, clear, and exact description of the same.

My invention relates to a machine designed to split the uppers of shoes in accordance with the general plan of splitting shown in Letters Patent granted to me on the 25th day of March, 1884, and in Letters Patent granted to W. A. Reed, August 19, 1884. In the patent first named the upper is split from the rear portion forward to a point where the opening of the front of the shoe terminates, and the second patent represents a similar form of splitting, except that the knife is inclined to the faces of the leather, so as to give the greater thickness to the lower edge of the rear portion on each side. As the leather is split part way between the sides, or from side to side all the way across, and from the rear to the point specified, when the upper and lower split portions are cut on the curved lines to give proper form to the side, two flaps are left, one on the upper and right-hand side and the other upon the lower and left-hand side. In forming the shoe out of these uppers it is necessary to shave off the flaps above described and to bevel smoothly on the line where the flap is removed.

The object of my present invention is, first, to split the leather only between those portions which form the two sides, and to leave those portions from which the flaps were split in the method described in the said patents unsplit and entire, so that the leather will remain in the parts covered by the flaps in said method in its original thickness.

The second object sought in my invention is to split and cut the leather in one operation.

In the accompanying drawings, Figure 1 shows a front view of the machine. Fig. 2 shows a like view with the rolls in different position. Fig. 3 shows a top view, partly in section. Fig. 4 is a plan view of the blank. Fig. 5 is a section on line xx of Fig. 2. Fig. 6 is a perspective view of the rollers with the knife in position. Fig. 7 is a perspective view

of an upper which is split through only a portion of the width of the leather, leaving the edges of full thickness.

Before describing the machine and mode of splitting I will explain, in reference to the blank and the shoe-upper made therefrom, (not herein claimed,) that the two forms shown in Figs. 4 and 7 involve the same principle. In Fig. 4 the part lying in rear of the line xy 55 x is split and the part lying in front is wholly unsplit. In Fig. 7 the part lying within the lines st is split and the remainder is wholly unsplit. The split portions form in the first case, Fig. 4, the counter, and the unsplit portions the front and sides of the shoe. In Fig. 7 the unsplit portions extend around the bottom of the counter, leaving the split in the upper parts. The mode of splitting, therefore, which is herein involved, as an improvement on the aforesaid patents, consists, essentially, in tapering the split portion of the blank from a point where the substantially parallel sides (xw in Fig. 4 and sv in Fig. 7) terminates to a point on the central longitudinal line 60 70 of the blank, or the front termination of the opening of the shoe, whereby the remainder of the blank about the edge is left of its original thickness, either all or part of the way around the shoe, accordingly as form Fig. 4 or Fig. 7 is used.

In the drawings, $A A$ represent the end pieces of the frame of the machine. The rollers $B B'$ are mounted in movable bearings C , each pair of which is pressed toward the other by springs and set-screws, the screws being shown at d , and the springs being interposed between the ends of the screws and the bearings, so that the rollers are pressed toward each other. I prefer, as shown in the drawings, to reverse the position of the set-screws and springs, placing them diagonally opposite, one above and the other below. This gives more stability to the other and brings the centers true. The belts are provided with 85 90 95 flanges $c c$, which fit accurately above and below over the contiguous parts of the end pieces, whereby the bearing-blocks are guided so that the alignment of the rolls is preserved, whether separated by the leather to a greater or less distance or pressed closely together when the leather is removed. The knife E is mounted 100

upon a standard, F, being adjustable thereon toward or from the rollers. The standard F is fixed to a plate, G, which turns on a pivot, g' . The knife is opposite the bite of the rollers, but is drawn into position inclined thereto by means of springs h h , when the mechanism hereinafter described permits the springs to act upon the plate. This mechanism consists of a cam, I, upon one end of each shaft. Both cams are exactly alike, and are shown in side elevation in Figs. 3 and 4. They are placed, however, in reverse position on the rollers, so that one bears on the edge of the knife on one side at one end, and the other bears upon the other side of the knife at the other end, and both, pressing on opposite sides of the pivot, tend in the same direction to turn the knife against the tension of the springs. The high part of the cam is a trifle higher than the periphery of the rolls, and the lower part of the cams is made to correspond with cut-away portions of the rolls shown at H H. It will be understood that the rolls turn inward toward each other, as indicated by the arrows in Fig. 1, and at the beginning of the operation of splitting an upper the edge of the knife rests against the higher part of the cams. The lower part of the cams and cut-away portions of the rolls then next to the knife, one on one side and one on the other, must travel outward and over in order to come in contact with the leather at the proper moment as it moves inward. It will be observed that the larger part of the rolls is cylindrical, and while the leather is moving over the cylindrical surface the edge of the knife is maintained by the high part of the cams in a plane nearly but not quite parallel with the surface of the rollers. The leather, therefore, is drawn in, being placed with its rear end foremost, and is split with a slightly-inclined split until the point x x of the leather reaches the knife, and at that time the points x' on the rolls reach the edge of the knife, one at one end and one at the other, the knife still riding on the high part of the cams. It must now be observed that the cut-away portions of the rolls correspond to the shape of the cut x y of the upper, and along this line the roll is cut down with nearly a perpendicular shoulder to a slight distance, and then is tapered down with the gradual winding curve, as represented in the drawings. Therefore, as the rolls pass on beyond this point, this cut-away edge on the line x' y' of each roll is brought snugly against the edge of the knife, which is allowed to tip more and more, by reason of the knife now riding on a constantly-diminishing part of the cam. This construction causes the knife on each end, when it strikes the point x' of the rollers, to cut out the leather from that point, and to follow this cut along the lines x' y' of the rolls; but as the rolls turn inward the points y' y' , being near the middle of the roll upon which they are placed, approach each other. Therefore the split portion grows narrower until it termi-

nates at a point at the lower part of the front opening of the shoe, and at that point the machine stops, and has to be turned backward to receive a new blank. I connect the knife to the standard by set-screws f f , which pass through slots in the knife E. The pivoted base plate G is also provided with adjusting-screws p' , which pass through it into grooves in the bottom plate on which the plate G turns. These serve to raise the whole bed-plate and

contents after the knife has been adjusted. 70 75

The rolls are connected by suitable gears as follows: A gear, o, on the shaft M (to which power is applied by a crank, as indicated) meshes with the gear m on the shaft of the roll B. On the other end of the shaft of M is the gear n, which, through an intermediate gear, q, is connected to a gear, p, on the shaft of 85 the roll B. By these gears the rolls are turned simultaneously and their opposing faces caused to move in the same direction. I have not considered it necessary to show mechanism for driving these gears beyond a simple 90 crank to indicate where the power is to be applied, nor means for reversing the mechanism when it reaches the end of the work, as described, automatic mechanism for this purpose being well known to those skilled in the art. 95 Any suitable automatic registering mechanism may also be used with the machine to register the number of uppers cut.

It will be understood that the cut-away portion of the rolls need not be of the precise 100 shape described, but may be varied according to the form of upper to be cut, as set forth in the aforesaid patents to myself and Reed. For instance, in Fig. 7 I represent an upper split through only a portion of the width of the 105 leather, leaving the edges which form the bottom of the counters of full thickness, and it will be obvious that a very simple change in the rolls would produce this effect.

I do not limit myself in this respect, nor in 110 respect to the means for supporting and moving the knife, as these may be varied indefinitely.

I do not herein claim the described blank or upper cut by the machine in the manner 115 described, as this constitutes the subject-matter of a separate application.

I claim—

1. The mode of forming a shoe-upper out of a blank of substantially the form described, 120 the said mode consisting in splitting the leather of the blank a part of the distance from the rear of the blank toward the front, said portion so split being of substantially equal width, and then tapering the split portions to a point on the central longitudinal line of the blank, whereby lateral unsplit portions of the leather are left, all substantially as set forth. 125

2. A machine for splitting uppers in accordance with the described plan, consisting of a pair of rollers having cylindrical portions and cut-away portions, said cut-away portions having the inclined sides terminating at or near the central line, and a knife arranged in the 130

described relation to the rollers and to the inclined sides of the cut-away portions thereof, substantially as described.

3. A machine for splitting uppers, consisting of a pair of rollers having cylindrical portions and cut-away portions, said cut-away portions having the inclined sides terminating at or near the central line, in combination with a knife and means, substantially as described,

for turning and varying the position of its edge, for the purpose set forth.

In testimony whereof I have signed my name to this specification in the presence of two subscribing witnesses.

GEORGE W. SLEEPER.
